DESIGN FOR A PICTURE DIALING DEVICE FOR A PHONOGRAPH RECORD

Melvin Shaw, Beverly Hills, and Robert Y. Allen,
Pacific Palisades, Calif.

Application November 26, 1947, Serial No. 142,824

Term of patent 14 years

(Cl. D25—1)

To all whom it may concern:

Be it known that we, Robert Y. Allen and Melvin Shaw, both citizens of the United States and residents of Pacific Palisades, California, and Beverly Hills, California, respectively, both in the county of Los Angeles, have invented a new, original, and ornamental Design for a Picture Dialing Device for a Phonograph Record, of which the following is a specification, reference being had to the accompanying drawing, forming part thereof.

In the drawing,

Figure 1 is a plan view of a picture dialing device for a phonograph record, showing our new design, and

Figure 2 is a top end view thereof.

The essential features of our new design are disclosed in full lines in the drawing.

The back of the device constituting our new design is identical with the front thereof.

We claim:

The ornamental design for a picture dialing device for a phonograph record, substantially as shown and described.

MELVIN SHAW.
ROBERT Y. ALLEN.
